ENVELOPE SEALING AND STAMPING DEVICE

Filed July 28, 1930

UNITED STATES PATENT OFFICE

MAX SKOLNIK, OF CHICAGO, ILLINOIS

ENVELOPE SEALING AND STAMPING DEVICE

Application filed July 29, 1930. Serial No. 471,245.

This invention relates to the sealing and stamping art, and especially to methods and means for sealing and stamping envelopes and the like.

5 The main objects of the invention are to provide an improved and simplified method of sealing and stamping envelopes; to provide improved and simplified means for practicing this method; to provide such 10 means of semi-automatic character adapted for ready use by unskilled operators; to provide for moistening the sealing and stamp receiving parts of an envelope by a simple manual manipulation of the envelope in two 15 corresponding ways, respectively, in relation to a common source of moisture in the process of sealing and stamping, and to provide a unitary sealing and stamp affixing implement of simple and improved construction 20 and operation.

This invention is illustrated by the accompanying drawings, in which:—

Figure 1 is a perspective view of the implement referred to.

25 Fig. 2 is mainly a central longitudinal section taken uprightly through the implement.

Fig. 3 is mainly a cross section on the line 3—3 of Fig. 2.

30 Fig. 4 is a cross section taken on the line 4—4 of Fig. 2.

Fig. 5 is mainly an enlarged face elevation of the stamp advance pawl and ratchet means, with the adjacent part of the housing frame shown in fragmentary form and part in section.

35 The implement 1 as a whole comprises an enclosed frame or housing 2, having a removable face plate 3 in combination with the moistening means 4 and stamp magazine 5, stamp feeding mechanism 6, and a stamp affixing plunger operated stamp applying mechanism 7.

The front end of the implement has a 45 horizontal, transverse, slot-like aperture 8 for admitting the flap and stamp receiving part of the envelope for moistening and stamp reception.

50 The moistening means 4 comprises a water-tight chamber 9 open at the top for holding water. In the back part of said chamber

is a partition 10, back of which is a wick or moisture feeder arranged to supply moisture to the upper front edge part of the aperture 8, whereby the envelope flap may be moistened when it is drawn through said aperture 55 and whereby the corner of the envelope may be moistened when it is thrust inwardly, as will be understood, for reception of a stamp.

The stamp magazine 5 is in the form of a chamber 14 wherein is mounted a removable 60 spindle or spool 15 having a strip 16 of stamps rolled thereon. A spring 18 secured to the housing wall bears frictionally upon the stamp roll to retard the feed thereof during the operation of the device. The feed mechanism 6 comprises a feed roll 20, which is operably connected to the stamp affixer 7. Beneath said roll is an upwardly bearing roller 22 mounted on the free end of an upwardly urged arm 23, which is pivoted at its op- 70 posite end 24 to the housing 2, a compression spring 25 being positioned to press upward medially on said arm.

The stamp affixer comprises a plunger rod 27 mounted slidably in an upright guide 75 part 28 of frame 2. This plunger on its lower end has a head face part 30, the back edge of which is formed to coat shearingly with a stationary member 32 on the frame, for clipping off the stamps successively and applying them to the envelope, as will be apparent. The upper end of aperture 27 is provided with an enlarged head 35 to serve as a handle for downward application of hand pressure. Said plunger is urged upwardly at all times by a compression spring 36, the tension of which is overcome by the downward hand pressure whenever a stamp is to be applied. 85

In using this device, a spool, charged with a roll of stamps, is set in place in the magazine 14, removal of the face plate 3 accommodating this operation. When the stamp spool is in place with the end of the stamp strip threaded between the rolls 20 and 22, 95 and projecting into the stamp affixing aperture 8, as shown in Fig. 2, the face plate is restored and then the device is ready for use.

When an envelope is to be sealed and stamped, the flap is first run lengthwise un- 100

der the lower end of wick 9, and then folded into place and the envelope is then drawn through the narrow aperture back of the sealing plate 37.

In applying the stamp the upper right-hand corner of the envelope is presented endwise into the aperture 8, so as to apply moisture properly from wick 9, and then when the envelope is in place under the plunger head 30, the first stamp on the stamp strip lies over the envelope, gummed side down. Then the plunger is depressed, whereby the stamp is sheared off and pressed down against the envelope, where it is instantly secured adhesively in place.

As the plunger descends the rearward arm extending from the head 30 moves the ratchet member counterclockwise. When the plunger is released, it is restored by the spring 36, and the arm on head 30 moves the ratchet member clockwise, which in this movement engages the feed roll 20 and advances the stamp roll for a distance equal to the length of one stamp. This sets the machine in position ready for the next envelope.

Although but one illustrated embodiment of this invention is herein shown and described, it is to be understood that some of the details may be altered or omitted without departing from the spirit of the invention as defined by the following claims.

I claim:

1. A device of the class described comprising a frame having a moisture reservoir and a wick communicating therewith and terminating in a moisture applying face of substantially the same width as the gummed edge of an envelope flap, said frame being formed to admit endwise passage of a gummed envelope edge past the wick face, and said frame having a spring pressure sealing attachment comprising a resilient strip secured at one edge to said frame, and arranged to admit a sealed envelope and press the gummed part of the flap against the envelope as the latter is drawn through said device.

2. An envelope sealing and stamping machine comprising a frame, a stamp applying plunger mounted medially thereon, a stamp magazine and feed mechanism back of said plunger, said mechanism being ratchet connected thereto, a spring secured to said frame for frictionally braking a roll of stamps in said magazine, a bearing roller directly below said feed mechanism, an arm whereon said roller is mounted, said arm being pivoted to the lower part of said frame, a spring urging said arm upwardly to press said roller against a stamp, moistening means in front of said plunger comprising a reservoir having a wick terminating downwardly in a moisture discharging face of oblong shape corresponding in dimension substantially with the width of a stamp and with the width of the flap sealing gummed zone of an envelope respec-

tively, and arranged broad side toward said plunger, said frame being formed to admit an envelope flap endwise past said wick, and to admit an envelope edgewise toward said plunger, and said frame having a spring pressure sealing attachment comprising a resilient strip secured to the end of said frame and fastened at the lower edge of said moistener, and arranged to admit endwise the sealing edge of an envelope and press the gummed part of the flap against the envelope as the latter is drawn through said device.

Signed at Chicago this 17th day of July, 1930.

MAX SKOLNIK.
